(57) **CLAIM**

The ornamental design for a toilet lid with back support, as shown and described.

DESCRIPTION

FIG. 1 is a perspective view of the toilet lid with back support, showing my new design, as part of a commode; FIG. 2 is a front view of the toilet lid with back support and commode of FIG. 1;

FIG. 3 is a top down view of the toilet lid with back support and commode of FIG. 1;

FIG. 4 is a side view of the toilet lid with back support and commode of FIG. 1;

FIG. 5 is a perspective view of the toilet lid with back support, shown in a different environment;

FIG. 6 is a front view of the toilet lid with back support of FIG. 5;

FIG. 7 is a side view of the toilet lid with back support of FIG. 5;

FIG. 8 is a upper view of the toilet lid with back support of FIGS. 5; and,

FIG. 9 is a lower view of the toilet lid with back support of FIG. 5.

The broken lines showing in the figures are only included for the purpose of illustrating the environment of the toilet lid with back support and form no part of the claimed design.
